UNITED STATES PATENT OFFICE.

WILLIAM S. WARD, OF PLANTSVILLE, CONNECTICUT, ASSIGNOR TO H. D. SMITH & CO., OF SAME PLACE.

WHIFFLETREE-COUPING.

SPECIFICATION forming part of Letters Patent No. 320,313, dated June 16, 1885.

Application filed April 13, 1885. (No model.)

To all whom it may concern:

Be it known that I, WILLIAM S. WARD, of Plantsville, in the county of Hartford and State of Connecticut, have invented certain new Improvements in Whiffletree-Couplings; and I do hereby declare the following, when taken in connection with accompanying drawings, and the letters of reference marked thereon, to be a full, clear, and exact description of the same, and which said drawings constitute part of this specification, and represent, in—

Figure 1, a rear view of the whiffletree bar and plate, showing the coupling; Fig. 2, a vertical central section through the coupling, showing the bolt; Fig. 3, an under side view of the plate attached to the whiffletree; Fig. 4, a top view of the socket attached to the whiffletree-bar, broken lines indicating the method of applying the whiffletree to the bar.

This invention relates to the device by which a whiffletree is coupled to the whiffletree-bar of a carriage, the object being the construction of the coupling so that the whiffletree may be readily detached or applied as occasion may require, and at the same time form an easy but anti-rattling joint upon which the whiffletree may play; and the invention consists in the construction, as hereinafter described, and more particularly recited in the claims.

A represents the whiffletree, B the whiffletree-bar.

On the whiffletree-bar the socket C is secured. This socket is a plate of metal having a central, preferably angular, opening, a, through it, and surrounding this opening a is a recess, b. A flange, d, around the central opening, extends above the upper plane of the socket, and from one side of the socket, say, the rear, is a horizontally-projecting flange, D. Into the recess b a ring of india-rubber or other suitable spring, e, is applied, and preferably upon this spring a thin metal washer, f, is arranged, as seen in Fig 2.

On the whiffletree A a plate, E, is fixed, corresponding to the socket, and as seen in Fig. 3. Centrally through the plate is an opening, h, corresponding to the flange d surrounding the central opening through the socket, and so that the flange on the socket may enter the opening in the plate, as seen in

Fig. 2. In the whiffletree, above the opening in the plate, a recess, l, is formed.

F is the whiffletree-bolt. This bolt has a head, m, and its neck n is of angular shape, 55 corresponding to the angular opening a in the socket. It is introduced through the plate E before the plate E is fixed to the whiffletree, with its head in the recess l in the whiffletree, and as seen in Fig. 2. An opening is made 60 through the whiffletree-bar corresponding to the opening in the socket, and through which the bolt extends. The lower end of the bolt is screw-threaded, and upon this screw-thread a nut, G, is applied. From the plate E a hook- 65 shaped extension is made, say to the rear, corresponding to the flange D on the socket, and so that when set together, as seen in Fig. 2, the hook-shaped projection on the plate E will engage with the flange D of the socket, as 70 seen in Fig. 2.

The whiffletree is applied by turning it to nearly right angles to the whiffletree-bar, and so that the hooked projection H may pass down to one side of the socket. Then when 75 the hooked portion has arrived into the plane of the flange D the whiffletree is turned to take the hook portion H into engagement with the flange D.

The extent of the flange D is sufficient to 80 prevent the ordinary working of the whiffletree from taking the hook out of engagement with the flange. The flange d on the socket, therefore, forms a central bearing on which the whiffletree may oscillate, while the flange D prevents the whiffletree from being lifted from its position on the socket. At the same time the bolt F draws the whiffletree down upon the spring in the socket with sufficient force to 85 prevent rattling, but not to interfere with the proper working of the whiffletree.

No strain comes upon the bolt other than that induced by the pressure upon the spring, the draft being taken entirely by the socket on the one part and plate on the other. 95

This coupling is applied by simply boring a hole through the one part for the bolt and a recess for the head of the bolt in the other part, the plate and the socket each being secured to its respective part independent of the 100 bolt, as indicated in Figs. 3 and 4.

Instead of applying the bolt with its head

in a recess in the whiffletree, it may be passed through the whiffletree with its head on the top of the whiffletree, in the usual manner of whiffletree-bolts; but I prefer to arrange the 5 head as I have first described.

I am aware that whiffletree-couplings have been constructed in two parts, the one with a recess and the other with a corresponding trunnion-like projection to enter the said recess and form a bearing on which the plates may turn, the trunnion adapted to interlock with the recess; but I make no claim to such construction.

I claim—

15 1. The combination of the socket C, constructed with a central opening through it, flange d around said opening extending above the plane of the plate, and also constructed with a recess, b, around said opening, and 20 also constructed with a flange, D, extending from one side in a horizontal plane, the said socket being adapted to be attached to the one part, with the plate E constructed for attachment to the other part, and with a central opening, h, corresponding to the flange d in the socket, and with a hook-shaped extension, H, corresponding to the flange D on the socket, a spring in the recess on the socket on which

said plate will bear, and a bolt adapted to bind said plate upon the socket, substantially as 30 described.

2. The combination of the socket C, constructed for attachment to the whiffletree-bar and with a central opening, a, and with a flange, d, around said opening projecting above 35 the plane of the socket, and with a recess, b, around said opening, and also with a flange, D, projecting from the socket in a horizontal plane, the plate E, constructed for attachment to the whiffletree, and with a hook-shaped projection, H, corresponding to the flange D on the socket, and with a central opening, h, corresponding to the flange around the opening in the socket, a spring in said recess upon 45 which said plate will bear, the bolt F, having its head adapted to bear upon the said plate, its neck of shape corresponding to the opening in the socket and adapted to pass through the whiffletree, and provided with a nut whereby the plate may be clamped upon the socket, 50 substantially as described.

WILLIAM S. WARD.
